(57) **CLAIM**

The ornamental design for a portion of a sharps container, as shown and described.

DESCRIPTION

FIG. 1 is a front perspective view of a portion of a sharps container of my new design;

FIG. 2 is a left side view of the portion of a sharps container of FIG. 1;

FIG. 3 is a right side view of the portion of a sharps container of FIG. 1;

FIG. 4 is a front end view of the portion of a sharps container of FIG. 1;

FIG. 5 is a rear end view of the portion of a sharps container of FIG. 1;

FIG. 6 is a bottom plan view of the portion of a sharps container of FIG. 1;

FIG. 7 is a top plan view of the portion of a sharps container of FIG. 1;

FIG. 8 is a front perspective view of an alternate embodiment of a portion of a sharps container of my new design;

FIG. 9 is a left side view of the portion of a sharps container of FIG. 8;

FIG. 10 is a right side view of the portion of a sharps container of FIG. 8;

FIG. 11 is a front end view of the portion of a sharps container of FIG. 8;

FIG. 12 is a rear end view of the portion of a sharps container of FIG. 8;

FIG. 13 is a bottom plan view of the portion of a sharps container of FIG. 8; and,

FIG. 14 is a top plan view of the portion of a sharps container of FIG. 8.
